VEHICLE LAMP

Bernard R. Weber, Elm Grove, and David W. Wendt,
Janesville, Wis., assignors to Wesbar Corporation, West
Bend, Wis.

Filed Oct. 25, 1972, Ser. No. 300,503

Term of patent 14 years

Int. Cl. D26—06

U.S. Cl. D48—32 R

FIG. 1

FIG. 4

FIG. 2

FIG. 5

FIG. 3

FIG. 6

FIG. 7

FIG. 8

FIG.9

FIG.12

FIG.10

FIG.13

FIG.11

FIG.14

FIG. 15

FIG. 16

FIG. 1 is a top plan of a vehicle lamp embodying the new design;

FIG. 2 is a left side view thereof;

FIG. 3 is a bottom view thereof;

FIG. 4 is a right side view thereof;

FIG. 5 is a rear view thereof;

FIG. 6 is a front view thereof;

FIG. 7 is a perspective view thereof and taken generally from the rear, left side;

FIG. 8 is a perspective view thereof and taken generally from the front, right side;

FIG. 9 is a top plan view of a modification of the lamp shown in FIGS. 1 to 8 inclusive;

FIG. 10 is a left side view thereof;

FIG. 11 is a bottom side view thereof;

FIG. 12 is a right side view thereof;

FIG. 13 is a rear side view thereof;

FIG. 14 is a front side view thereof;

FIG. 15 is a perspective view thereof and taken generally from the right rear side; and

FIG. 16 is a perspective view thereof and taken generally from the left front side thereof.

The faceting is partially shown in FIGS. 2, 5, 7, 12, 13 and 15 for convenience of illustration, it being understood that the faceting is uniformly continuous over the areas on which it is indicated.

We claim:

The ornamental design for a vehicle lamp, substantially as shown and described.
